US00D917341S

(12) **United States Design Patent** (10) **Patent No.:** **US D917,341 S**
(45) **Date of Patent:** **** Apr. 27, 2021**

(54) **DELIVERY AUTONOMOUS GROUND VEHICLE**

(71) Applicant: **Amazon Technologies, Inc.**, Seattle, WA (US)

(72) Inventors: **Gregory Katz**, San Francisco, CA (US); **Christopher Jones**, San Francisco, CA (US); **Ennio Claretti**, Seattle, WA (US); **Robert Curtis**, San Francisco, CA (US); **Nicolas Hostein**, Seattle, WA (US); **Peter Johnson**, Seattle, WA (US); **Nicolas Kureczewski**, Seattle, WA (US); **Sean Scott**, Sammamish, WA (US); **Brett Skaloud**, Seattle, WA (US); **Andrew Stubbs**, Seattle, WA (US); **Scott Waters**, Hollis, NH (US)

(73) Assignee: **Amazon Technologies, Inc.**, Seattle, WA (US)

(**) Term: **15 Years**

(21) Appl. No.: **29/672,893**

(22) Filed: **Dec. 10, 2018**

(51) **LOC (13) Cl.** **12-13**
(52) **U.S. Cl.** **D12/86**

(57) **CLAIM**

The ornamental design for a delivery autonomous ground vehicle, as shown and described.

DESCRIPTION

FIG. 1 is a front top perspective view of a delivery autonomous ground vehicle according to our new design;
FIG. 2 is a rear top perspective view thereof;
FIG. 3 is a front bottom perspective view thereof;
FIG. 4 is a rear bottom perspective view thereof;
FIG. 5 is a front end view thereof;
FIG. 6 is a rear end view thereof;
FIG. 7 is a side view thereof;
FIG. 8 is side view thereof, opposite of the view of FIG. 7;
FIG. 9 is a top view thereof; and,
FIG. 10 is a bottom view thereof.

The broken lines depict portions of the delivery autonomous ground vehicle that form no part of the claimed design.

1 Claim, 9 Drawing Sheets
